UNITED STATES PATENT OFFICE.

WILLIAM I. BALDWIN AND EVERETT A. KLINE, OF CHAGRIN FALLS, OHIO.

PAPER-BAG MACHINE.

SPECIFICATION forming part of Letters Patent No. 703,635, dated July 1, 1902.

Application filed January 15, 1900. Serial No. 1,452. (No model.)

To all whom it may concern:

Be it known that we, WILLIAM I. BALDWIN and EVERETT A. KLINE, citizens of the United States, residing at Chagrin Falls, in the 5 county of Cuyahoga and State of Ohio, have jointly invented certain new and useful Improvements in Paper-Bag Machines; and we do declare the following to be a full, clear, and exact description of the invention, such 10 as will enable others skilled in the art to which it appertains to make and use the same, reference being had to the accompanying drawings, and to the letters of reference marked thereon, which form a part of this 15 specification.

This invention relates to an improvement in paper-bag machines, and more particularly to machines of the type shown in United States Letters Patent to Charles B. Stillwell, 20 No. 206,638, dated July 30, 1878. In the said Stillwell machine suitable fixed guides are employed, the same being adjusted at U in the patent. It has been found that these 25 fixed guides often cause the bags to clog, and thus interfere with the working of the machine. Our invention is designed to overcome such defect by substituting movable guides for the fixed guides and by the special arrangement of the guides and their associated 30 instrumentalities.

In the drawings we have shown the invention in its useful application; but inasmuch as the same can be employed in connection with other machines and resides wholly in 35 the guides and their associated parts we do not show a full operative bag-machine, but simply an operative structure of movable guides and carrying-belts with rollers and drums.

40 A construction to which our invention is readily applied is that shown in the aforesaid patent and in the patent to William Liddell, No. 492,498, dated February 28, 1893. The drawings may therefore be said to be largely 45 diagrammatic.

In the drawings, Figure 1 is a side elevation, partly in section. Fig. 2 is an end elevation, showing parts in section. Fig. 3 is a detail section on line 3 3 of Fig. 1.

50 In the drawings, A designates the frame of

the machine, in which is mounted a cylinder B. Associated with this cylinder are the various instrumentalities for forming the bag; but inasmuch as such features are not a part of our present invention we have omitted 55 them from the drawings.

C designates carrier-belts extending around the pulleys C', rollers C²C³, and creasing-cylinder C⁴. These belts also extend partially over the pulley-wheels G G' at each end of 60 the cylinder B in the usual manner and are carried forward over a pressing and driving roll C⁵ near the front of the machine and thence over a pressing-roll D, mounted in the suitable bracket C⁶. The existence and purpose 65 of these carrier-belts C and the various rolls are well understood in the art. The cylinder C⁴ corresponds to the cylinder O in the patent to Stillwell, above mentioned, the cylinder B to the cylinder L therein, the pulleys 70 G G' to l l' therein, the roll C⁵ to S therein, and the belts C to the belts p therein.

Heretofore the partially-formed bags during treatment have passed around cylinder B, being caught at their edges between the 75 belts C and pulleys G G' and while so held have passed around the main cylinder B and been discharged onto suitable guides and by continued movement with the belt C were carried up and back for final treatment. 80 These metal guides were, as above stated, objectionable, and to avoid this objection we employ the supplemental carrier-belts F and F'. These belts F and F' are arranged to pass around the pulleys G and G' under the 85 belts C. Said pulleys are arranged at each end of the cylinder B and loose on the shaft thereof, so as to move independently of the cylinder, as shown in said patent to Stillwell. The diameter of these pulleys is preferably 90 slightly less than that of the cylinder, so that the outer surface of the new belts F F' is flush with that of the cylinder, as shown in Fig. 3. These belts pass over the pulleys G G' and thence around the driving-cylinder 95 C⁵, then up over the idler H, and thence forward over the tension-roller H' back to the pulleys. They receive their motion from the cylinder C⁶, which is driven by the power-belt. (Shown in dotted lines.) To preserve 100

the necessary tension on the belts F F', the rolls H' are employed, the same being mounted on arms h', pivotally connected with the uprights K on the machine. The rolls are held at an angle to the uprights, as shown.

h² designates an idler mounted in the uprights K and serves to give the proper angle to the belts, so that the rolls H' may effect their tensioning purpose.

10 L designates a pressing-roll mounted on a crank-arm L', having a spring L² connected to one end, so that the tendency will be to force the bags into contact with the surface of the pressing-roll C⁵.

15 In operation the bags in process of formation pass around the cylinder B and are caught at their side edges between the belts C C and F F' at the place marked E as they pass the first creasing-cylinder. They are then held

20 and carried between the two pairs of belts during their subsequent passage around the main cylinder B and pressing-roll C⁵ to the roller D, whence they are discharged onto old carrying means to be conveyed away.

25 All four of the belts C C F F' are driven at the same speed, but slightly faster than the cylinder B, so that a proper tension of the blanks while passing around the cylinder is insured. The roll L, acting against the roll

30 C⁵, operates as a pressure-roll for the bags as they pass around the roll C⁵, and the movement of the belts prevents any clogging of the blanks.

From the above description it will be seen
35 that our invention resides in the supplemen-

tal carrying-belts F F' and their tension-wheels and the associated pressure-roll L.

Having thus described the invention, what we claim as new, and desire to secure by Letters Patent, is—

40

1. In a paper-bag machine, the combination with the cylinder B, pulleys at opposite ends thereof, and two carrying-belts running one above the other on each of said pulleys, a driving-roll for the belts, and means for 45 tensioning said belts.

2. In a paper-bag machine, the combination with the cylinder B and pulleys at opposite ends thereof, of a driving-roll, carrying-belts running on said pulleys and passing 50 around said driving-roll, and a spring-actuated pressure-roll adjacent to said driving-roll and actuating against the same, substantially as described.

3. In a bag-machine, the combination with 55 the cylinder, of pulleys at opposite ends thereof of less diameter than the cylinder, two carrying-belts running one above the other on each of said pulleys, the outer face of the inner belt being substantially flush 60 with the periphery of the cylinder, and means to drive the belts.

In testimony whereof we affix our signatures in presence of two witnesses.

WM. I. BALDWIN.
EVERETT A. KLINE.
